UNITED STATES PATENT OFFICE

159,947

FIRESIDE BENCH

William Rex Bell, Terre Haute, Ind.

Application November 17, 1948, Serial No. 149,679

Term of patent 3½ years

(Cl. D15—11)

To all whom it may concern:

Be it known that I, William Rex Bell, a citizen of the United States, residing at Terre Haute, in the county of Vigo and State of Indiana, have invented a new, original, and ornamental Design for a Fireside Bench, of which the following is a specification, reference being had to the accompanying drawing, forming part thereof.

Fig. 1 is a perspective view of a fireside bench, showing my new design.

Fig. 2 is an end elevation thereof looking toward the left hand end of the bench as shown in Fig. 1.

I claim:

The ornamental design for a fireside bench, substantially as shown.

WILLIAM REX BELL.
